UNITED STATES PATENT OFFICE.

ARTHUR JONES, OF BELLEVILLE, ILLINOIS.

ELECTRIC FURNACE.

1,414,362.

Specification of Letters Patent.

Patented May 2, 1922.

Application filed May 13, 1920. Serial No. 380,990.

To all whom it may concern:

Be it known that I, ARTHUR JONES, a citizen of the United States of America, residing at Belleville, county of St. Clair, State 5 of Illinois, U. S. A., have invented a certain new and useful Electric Furnace, of which the following is such a full, clear, and exact 10 description as will enable any one skilled in the art to which it appertains to make and 15 use the same, reference being had to the accompanying drawings, forming part of this specification.

My invention relates to an electric furnace and more particularly to that type of furnace in which the melting chamber is capable of rotation on a horizontal axis during the operation of smelting and is also rotatable in a vertical plane to discharge the metal. Many of the features of my invention 20 however are applicable to other types of electric furnaces.

One object of my invention is to provide means for rotating the electrodes of an electric furnace in order to prevent the electrodes from becoming cemented in their bearings by the condensed fumes of volatile metals such as zinc. Such rotation of the electrodes also prevents the possibility of the electrodes sagging should they become 25 soft under the intense heat of the furnace, and taken in connection with the proper angular disposition of the carbons also maintains proper points upon carbons and thus maintains the arc in the proper position. 30 Another object of my invention is to provide improved means for feeding the carbons to control the arc. Another object of my invention is to provide improved means for cooling the carbon holders.

40 In the accompanying drawings which illustrate one form of electric furnace made in accordance with my invention Figure 1 is a horizontal central section. Figure 2 is a side elevation, the carbon feeding mechanism being broken away. Figures 3 and 4 are enlarged views showing details of construction. Figure 5 is a section taken on the line 5—5 of Figure 2. Figure 6 is an enlarged detailed view of the carbon feeding mechanism showing a modification for controlling the feed electrically. Figure 7 is an end view of the parts shown in Figure 6. Figure 8 is an enlarged section taken on the line 8—8 of Figure 6. Figure 9 is a 55 section taken on the line 9—9 of Figure 8, the carbon being omitted. Figure 10 is a

view similar to Figure 7 but showing manually operated means for controlling the feed. Figure 11 is a diagrammatic view illustrating the water cooling system, and 60 Figure 12 is a detail view showing the automatic stop for the electrode feeding mechanism.

The furnace is supported by any suitable means such for instance as the two standards 65 10 in which are journaled trunnions 11 and 12 respectively. The trunnions 11 and 12 carry cross bars 13 on which are mounted a pair of annular members 14 in which are journaled wheels 15 supporting the body of 70 a furnace. The body of the furnace consists of a central sleeve 16 and end pieces 17 and 18 respectively bolted thereto and each provided with a flange 19 forming a track for engaging with the wheels 15 in the corresponding annular members 14. The end piece 18 is preferably formed of two parts bolted together at 20 as best shown in Figure 75 1 of the drawings. The body of the furnace is provided with the usual lining 21 of fire 80 clay or other factory material and has its rear end substantially hemispherical in form as shown at 22, the front end being provided with a charging portion orifice 23 closed by a door 24. A heat insulating lining 25 is 85 preferably placed between the lining 21 at the shell of the furnace. Secured to the central part 16 of the shell is a bevel gear 26 meshing with a bevel gear 27 carried on the sleeve 28. Passing through the trunnion 11 90 and having secured to it a worm wheel 29 and engaging with a worm 30 carried on it with the uprights 10 as best shown in Figure 3. The worm 30 is revolved by gearing 31 driven from any source of power so as to 95 continuously rotate the furnace on its longitudinal axis during the operation of smelting. The wheels 15 hereinabove referred to are shown as provided with single flange. In case the distance between the tracks 19 100 is considerable it is desirable to have wheels 15^a on one of the tracks provided with two flanges as shown in Figure 4 of the drawings so that the expansion and contraction of the furnace shell will not throw the slip rings hereafter to be described out of relative position. The furnace is provided with carbon electrodes 35 which as shown in the drawing are two in number. The number however may be varied. The electrodes 35 105 are arranged at an angle to each other as best shown in Figure 1 of the drawings and 110

the points are arranged to meet substantially in the center of the hemispherically rear end of the melting chamber. Each of the carbons 35 passes through a split sleeve 36 as best shown in Figures 8 and 9 which sleeve is adapted to be clamped against the carbon by means of threaded rings 37 and 38 which rings move said sleeve 36 longitudinally relative to a surrounding collar 39, the contacting surface of the parts 36 and 39 being cone shaped as shown in Figure 9 of the drawings. The collar 39 is carried by a casing 40 having a chamber 41 forming a water jacket. Secured to the casing 40 are bearings 42, 43, 44, and 45 respectively. In the bearing 45 is journaled a sleeve 46 having a key connection to the shaft 47. The sleeve 46 carries a gear wheel 48 meshing with a gear wheel 49 secured to the sleeve 39 hereinbefore described. In order to prevent short circuiting of the device one or more of the gear wheels 48 and 49 are made of insulating material. The sleeve 46 is prevented from moving longitudinally with relativity to the bearing 45 by the gear wheel 48 and a collar 46. The inner end of the shaft 47 is provided with a beveled gear wheel 50 meshing with a wheel 51 driven from a motor 52 by means of gearing 53 as shown in Figure 1 of the drawings. The outer end of the shaft 47 is journaled in an annular member 54 and is provided with a pair of beveled gear wheels 55 turning loosely on it and meshing with beveled gear wheel 56. Keyed to the shaft 47 between the wheels 55 is a friction clutch 74 adapted to engage with either of said wheels 55. In order to feed the carbon forward or backward this beveled gear wheel 56 is mounted on one end of a shaft 57. The opposite end of which carries a beveled gear wheel 58 meshing with a wheel 59 secured on the end of a threaded rod 60 passing through the bearing 44 which is correspondingly threaded so that the rotation of the rod 60 will feed the casing 40 with its attached carbon toward or away from the central point of the furnace. The bearing 43 surrounds a rod 61, adapted to carry the current to the electrode. This rod 61 is preferably insulated from the annular member 54 and an annular member 62 carrying the opposite end of the rod by insulating bushings 63. 64 is a binding post for conveying the current to the rod 61. The bearing 42 surrounds a rod 65 which merely serves as a guide for the member 40. The bearings 42, 44, and 46 are insulated from the member 40 by insulating plates 66. One or the other of the beveled gear wheels 55 is adapted to be operatively connected with the gear wheel 56 either automatically by a pair of electromagnets 68 acting upon a lever 69 engaging with it clutch 74 or manually by moving a handle 70, (Figure 10) actuating a lever 71

to shift the said clutch 74. Whether the clutch 74 is operated automatically by the electromagnets 68 or manually it is desirable to throw the feeding mechanism out of gear automatically when the member 40 has traveled to a point adjacent to either the annular member 54 or the annular member 62. This I may accomplish by means of a mechanism shown in Figure 12 in which the shaft 65 is made hollow and contains a rod 72 having projecting fingers 73 adapted to be struck by the member 40 to automatically move the lever 71.

The current may be carried to the carbons 35 by means of slip rings 77 held by any suitable mechanism not shown, in the end of the trunnion 12 and making contact with conductors 76 passing through the said trunnion and bearing on slip rings 75 carried by the cylindrical portion 16 of the shell. From the slip rings 75 the current is carried to the binding post 64 hereinbefore referred to by wires, not shown. The trunnion 12 is provided with a worm wheel 78 driven in a manner similar to the worm wheel 29 hereinbefore described when it is desired to turn the furnace upon the trunnions 11 and 12.

In order to cool the carbons and the carbon holders I provide water pipes 79 passing through the sleeve 28 and connected with the compartments of a duplex water chamber as best shown in Figure 11. This duplex water chamber consists of an outer annular member 80 carried from one of the members 14 by means of brackets 81 and an inner annular member 82 provided with a partition 83 and carried from the part 17 of the furnace shell by brackets 84. From this duplex annular chamber the water is carried through coils 85 surrounding the carbons within the furnace lining and through the water jacket 41 to and from which the water is conducted by means of flexible pipes 86 as shown in Figure 11.

The operation of my furnace is as follows: The furnace is charged through the opening 23 while in horizontal position thus obviating danger of injuring the carbons 35. After the furnace is charged and the door 24 closed current is passed through the electrodes 35 forming an arc between the points of the said electrodes substantially in the center of the curved rear end of the combustion chamber. This arc is controlled either automatically or manually by moving the carbons toward and away from this central point by the mechanism hereinbefore described. Whether the carbons are being fed forward or backward or are longitudinally stationary they are continually revolved by means of the motor 52. Such rotary movement of the carbon prevents the carbons from being cemented into their bearings by the fumes of volatile metals, such as zinc.

This rotation of the carbons also prevents the carbons from sagging down when they are softened by the heat of the furnace and also preserves the shape of the points of the 5 carbon so that the arc can be properly controlled. It is to be noted that the carbons revolve in the same direction whether being fed forward or backward so that in case of 10 long carbons formed of two or more parts there is no tendency to unscrew the joints of the carbon when feeding in either direction.

Having fully described my invention, what 15 I claim as new and desire to secure by Letters Patent of the United States is:

1. In an electric furnace, the combination 20 with a melting chamber of a plurality of electrodes angularly arranged with relation to each other and means for rotating said electrodes during the operation of the furnace to maintain the form of the electrode points.

2. In an electric furnace, the combination 25 with a melting chamber, of an electrode projecting into said chamber, means for continuously rotating said electrode during the operation of the furnace, reversible electrode feeding mechanism and means for throwing said feeding mechanism into and out of operative relation with said electrode feeding 30 mechanism whereby the electrode is rotated in the same direction when feeding in either direction.

3. In an electric furnace, the combination 35 with a melting chamber having a substantially hemispherical integral end, of an electrode projecting into said chamber through said hemispherical end and arranged to produce an arc approximately in the center of 40 curvature of said end.

4. In an electric furnace, the combination 45 with a melting chamber having a substantially hemispherical integral end, of a pair of electrodes projecting into said chamber through said integral end and arranged at an angle to each other to produce between them an arc approximately in the center of 50 curvature of said end.

5. In an electric furnace, the combination 55 with a melting chamber having a closed end, of electrodes projecting through the closed end for producing an arc between them ad-

jacent thereto, said chamber being provided with a charging aperture at the opposite end. 55

6. The combination with a rotating electric furnace, a tilting frame in which said furnace is mounted, a duplex annular chamber carried by one of said parts and having sliding contact with a member carried by the 60 other of said parts, and electrode for said furnace and water cooling connections for said electrode comprising said duplex annular chamber.

7. In an electric furnace, the combination 65 with a melting chamber, of an electrode projecting into said chamber, means for rotating said electrode during the operation of the furnace, feeding mechanism for said electrode said feeding mechanism being reversible independent of said rotating means, 70 and automatic means for limiting the movement of said feeding mechanism in either direction.

8. In an electric furnace, the combination 75 with melting chamber, of a plurality of electrodes projecting into said chamber, means for rotating said electrodes during the operation of the furnace, independent feeding mechanism for each electrode, and 80 means for operating said feeding mechanism from said electrode rotating mechanism.

9. In an electric furnace, the combination 85 with a melting chamber having a closed end, of a plurality of electrodes projecting through said closed end and arranged at an angle to each other to produce an arc adjacent to said closed end, said chamber being provided with a charging aperture at the 90 opposite end.

10. In an electric furnace, the combination 95 with a melting chamber having a closed end, of a plurality of electrodes arranged at an angle to each other for producing an arc adjacent to said closed end, and means for rotating said electrode during the operation of the furnace to maintain the shape of their points, said chamber being provided with a charging aperture at the opposite end. 100

In testimony whereof, I have hereunto set my hand and affixed my seal.

ARTHUR JONES. [L.S.]
